(57) **CLAIM**

The ornamental design for a display package for tool belts and related products, as shown and described.

DESCRIPTION

FIG. 1 is a front plan view of an embodiment of a display package for tool belts and related products (shown in phantom) according to the present invention;
FIG. 2 is a right side view thereof;
FIG. 3 is a left side view thereof;
FIG. 4 is a front plan view thereof;
FIG. 5 is a top view thereof;
FIG. 6 is a bottom view thereof; and,
FIG. 7 is a rear plan view thereof.

The broken line showing of products is for illustrative purpose only and forms no part of the claimed design.
